ARTICLE FEEDER FOR CAN MAKING MACHINES

William F. Butler, Hillside, N. J., assignor to
American Can Company, New York, N. Y., a
corporation of New Jersey

Original application June 23, 1933, Serial No.
677,323. Divided and this application November
14, 1935, Serial No. 49,838

5 Claims. (Cl. 198—33)

The present invention relates to container or can making machines and has particular reference to mechanism for feeding articles such as can parts and for inverting or turning the articles over while they are being fed. This is a division of my United States Patent No. 2,085,001, issued June 29, 1937, on Flange curling machine.

The invention contemplates the provision of a mechanism which may be utilized as a part of a can machine and which receives the can parts in one position and reverses or turns them over so that they are in proper reversed position for a subsequent operation, it being convenient in many associated can manufacturing operations to have the can parts in one position for the first operation and in a reversed position for a succeeding operation.

It is therefore an object of the present invention to provide an apparatus for receiving can parts in one position and for delivering them into a can making machine or the like, the while inverting or turning them over.

Another object is the provision of devices of this character for feeding the can parts into and out of the inverting or turn over element in time with the movement of the latter.

Numerous other objects and advantages of the invention will be apparent as it is better understood from the following description, which, taken in connection with the accompanying drawings, discloses a preferred embodiment thereof.

Referring to the drawings:

Figure 1 is a plan view of a mechanism embodying the instant invention, with parts broken away;

Fig. 2 is a longitudinal section of the mechanism taken substantially along the broken line 2—2 in Fig. 1;

Fig. 3 is a transverse sectional view taken substantially along the line 3—3 in Fig. 2; and

Fig. 4 is a sectional detail taken substantially along the line 4—4 in Fig. 3.

The mechanism of the instant invention is adapted to handle such articles as metal sheets, can body blanks, partially formed bodies, can ends, and the like. In the manufacture of such articles, as for example, can ends, which are usually formed in a drawing press, it is most convenient to draw the central panel of the ends upwardly in an inverted position. However, for subsequent operations on the ends such as a curling or other operation, it is most convenient to have the ends right side up. Therefore, for the purposes of this specification oblong can

ends 21 (Fig. 1) are used as an exemplary form of article to be operated on by the instant mechanism.

In the mechanism disclosed in the drawings as a preferred embodiment of the present invention, the oblong can ends 21 are received in the upper end of an inclined chute 22 (Figs. 2 and 3) located at one end of the mechanism. This chute is preferably mounted upon a bracket extension 23 of a frame 24 which may be the main frame of a curling machine. An intermittently movable turnover wheel 25 is carried on a horizontal shaft 26 journaled in bearings 27 formed in the frame bracket 23 and this turnover wheel is directly below the discharge or lower end of the chute 22.

The can ends 21 move by gravity in a line down the chute 22, the line of ends being held in the chute by yielding devices 28 which engage the lowermost can end at a station A (Fig. 2). These ends are all faced the same way as they rest in processional order in the chute and where they are coming direct from a drawing and end forming press their central panel sections are faced upwardly as shown. In this position they will be inserted into the turnover wheel 25 and turned over.

The turnover wheel 25 comprises a pair of spaced discs 31 (Figs. 1 and 2) which are held on the shaft 26 by setscrews 30. This construction permits movement or adjustment of the discs on the shaft so that they may be set to accommodate different sizes of can ends. The inner face of each disc 31 is cut across with grooves 32 which extend from the periphery of the disc generally toward the center but offset a slight distance. The outer or peripheral end of each groove flares outwardly at 33, these groove ends in each disc being equally spaced around its periphery. A pair of flared groove mouths 33, one on each disc, are brought into register (at a station B) with the lower discharge end of the chute 22 at each rest period of the turnover wheel.

The discs 31 are moved as their supporting shaft 26 is intermittently rotated in a clockwise direction as viewed in Fig. 2, and at each movement a new pair of grooves 32 is presented to the discharge end of the chute (station B). Feeding devices 35 operate when the discs 31 are at rest to move the lowermost can end 21 from its held position within the yielding devices 28 (station A) and to insert it into the aligned grooves at station B.

The top part of the frame 24 is formed as a

horizontal table 36 (Figs. 1 and 3) and it is along this table that the can ends are moved after they have been turned over by the discs 31. In this turn-over operation the can end 21 fed into

- 5 the grooves 32 of the discs 31 at station B, is carried up and over in two succeeding step movements of the discs through two idle stations C and D and at the third step movement is brought into its third position of rest at a station marked 10 E in Fig. 2.

10 The end is now in a horizontal position and is in substantial alignment with the top of the table 36. In the three step movements just described the can end has been turned over from 15 the inclined position with its panel face up into horizontal position with its panel face down.

Transfer devices 41 (Fig. 2) operate in a horizontal plane and along the table 36 to remove the turned-over end from the discs 31 at the 20 station E and to advance it into the curling machine or other device.

25 Referring more in detail to the drawings, the feeding chute 22 (Figs. 1, 2 and 3) is preferably formed by a pair of spaced blocks 55 each of which is secured by bolts 56 to the bracket 23. These blocks are movable or adjustable on the bracket 23 for different sizes of can ends and when bolted in position they are separated a distance slightly in excess of the drawn central 30 panel (designated by the numeral 57) of the end 21. The panel of each end is surrounded by an outwardly extending flange (marked 58).

35 A grooved guide rail 59 is mounted on each block 55 adjacent its inner edge and opposite sides of the flange 58 of the ends pass into and move along these grooves as the ends slide by gravity down the inclined chute. It is the lowermost can end of the line of ends in the chute that is engaged by the yielding devices 28, as 40 previously described.

45 These yielding devices comprise fingers 61 which are carried on pivot screws 62 threaded into the blocks 55 adjacent their upper surfaces. The lower end of each finger 61 is held in the path of travel of the can ends by a leaf spring 63 which is secured to a projection 64 extending outwardly from the surface of the block. The spring engages the finger near its pivot screw 62. The upper end of each finger 61 when holding 50 a can end rests against the end of an adjusting screw 65 which is threaded into the projection 64 and which may be adjusted to position the lower end of its associated finger. A small block 66 is secured upon the upper face 55 of each block 55 and provides a guide for the can end as it moves from the chute.

55 The feeding device 35 for moving the lowermost can end from the chute and for placing it into the turnover wheel 25 is best shown in Fig. 60 2. This feeding device comprises a finger 71 which is mounted on a pivot pin 72 carried in a hollow block 73 which slides up and down on an inclined strap 74. The strap is secured at its upper end to the bracket 23 by a bolt 75 and at its lower end to the table 36 by a bolt 76.

65 Strap 74 is located beneath and centrally of the can end travel through the chute and its upper end extends to a point beyond or above the pivoted fingers 61. The lower end of the strap 70 is formed with a collar section 77 (Figs. 1 and 2) which encircles the shaft 26 intermediate the discs 31.

75 Movement of the block 73 to its upper or raised position arranges its finger 71 under the lowermost cover 21. A leaf spring 78 carried in the

block and resting under the finger yieldingly moves it into position for engagement with the lower vertical wall of the end panel 57 at such a time.

80 The block 73 and the finger 71 are now moved down or into their lowered position to effect the removal of the engaged can end 21 from the chute. In this movement the can end is forced between and past the lower ends of the fingers 61 which move back against the action of their springs 63 10 and permit the can end to pass between the blocks 66 and into a pair of presented grooves 32 of the turnover discs 31. The springs 63 move the fingers 61 inwardly as soon as the can end moves past them, which action holds back the remainder of the line of can ends.

15 To effect this up and down movement of the block 73 on the strap 74 the block is pivotally connected by a pin 81 to the upper end of a bent connecting strap 82 (Figs. 2 and 3). This strap 20 82 is pivoted at 83 to an outer arm 84 of a compound crank arm 85 formed on one end of a horizontal shaft 86. The shaft 86 is journaled in bearing 87 formed in the frame 24 and supports a spur gear 88 which may be a main driving gear or may be a gear driven from and in time with the main driving mechanism of the curling machine.

25 Rotation of the gear 88 is transmitted to the shaft 86 which in turn carries the crank arm 85 30 around and this actuates the block 73 and its finger 71 for a feeding stroke while the intermittently rotated turnover wheel 25 is at rest.

35 The intermittent actuation of the turnover wheel 25 is effected by means of devices which impart step rotation to the shaft 26 in the following manner. The shaft 26 carries a sprocket 105 (Figs. 1, 3 and 4) over which a chain 106 operates. This chain also passes over a sprocket 107 which rotates on a Geneva wheel stationary shaft 108 40 fixed in a bearing 109 formed in the frame 24.

45 The sprocket 107 is secured to or is an integral part of a Geneva wheel 115 which is intermittently rotated on the shaft 108 by a roller 116 (Fig. 4) engaging in radial slots 117 formed in the Geneva wheel. The roller 116 is mounted on a pin 118 extending outwardly from one face of the gear 88. The hub of the gear 88, designated by the numeral 119, is cut away at 121 to permit movement of the Geneva wheel 115 by engagement of the roller 116 within each slot 117.

50 The uncut part of this hub 119 provides for the locking of the Geneva wheel on its rest period by rotating within pockets 122 formed in the wheel, this being a usual Geneva unit construction. By the described connection, the continual rotation of the shaft 86 is imparted as an intermittent movement to the shaft 26 and the latter advances the turnover discs 31 in a step by step movement to turn over a can end carried therein 60 and to bring it to a horizontal position opposite the table 36 at the station E.

55 Removal of the can end from the turnover wheel 25 by the transfer devices 41 now follows. A feed bar 125 (Figs. 1, 2 and 3) is provided as 65 part of such devices. This feed bar moves back and forth in a longitudinal inverted T shaped slot 126 formed in the table 36. The bar in cross section has the same general inverted T shaped form as the slot, which form holds it against 70 upward displacement in the slot.

75 As the turnover wheel brings the can end 21 into its horizontal position at station E, the feed bar is in its rear position (Fig. 2). A fixed finger 131 is formed on the rear end of the feed bar 75

and projects upwardly above the surface of the table. This finger 131 is behind the can end as it comes to rest in station E.

While the turnover wheel remains stationary 5 on its period of rest (Figs. 2 and 3) the feed bar moves forward and the finger 131, engaging the can end, slides it out of its grooves 32 and over the surface of the table 36.

To effect this feeding movement the feed bar 10 125 at its rear end has rack teeth 132 cut in its lower face. These teeth are engaged by a segmental rack 133 formed on the upper end of an arm 134 which is secured to a rock shaft 135 (Figs. 2 and 3). Shaft 135 is mounted in a boss 15 136 formed in the frame 24. The arm 134 is cut out in its central section to provide a rectangular opening 137.

The compound crank 85 extends through the opening 137, the rear part being connected with 20 the outer arm 84 by a cylindrical section 138 (Fig. 3). A pair of split blocks 139 encircle and provide a bearing for the cylindrical part 138 and these have sliding movement within the opening 137 of the arm 134. As the double crank moves 25 with the rotation of its shaft 86, the cylindrical part 138 of the arm is carried in a circular short crank path, the pivot 83 of the strap 82 describing the full or long crank movement. It is these two movements that constitute the double crank 30 action.

The short action causes the blocks 139 to slide up and down within the opening 137 and to transmit a rocking motion to the arm 134 with its rock shaft 135. The resulting rocking movement 35 of the segmental rack 133, through the rack section 132 of the feed bar, moves the latter back and forth within its table slot 126. Thus the can ends are removed from the turnover wheel 25 and are advanced across the top of the table 36 toward the work performing elements of the curling machine. The ends are guided during this 40 travel by spaced parallel guide rails 141 (Fig. 1) which are secured to the top of the table and are adjustable for different sizes of can ends.

It is thought that the invention and many of 45 its attendant advantages will be understood from the foregoing description, and it will be apparent that various changes may be made in the form, construction and arrangement of the parts without departing from the spirit and scope of the 50 invention or sacrificing all of its material advantages, the form hereinbefore described being merely a preferred embodiment thereof.

I claim:

1. An apparatus for handling articles such as 55 can parts and the like, comprising in combination, a chute for said articles, spring controlled yieldable devices in said chute for holding said articles therein, a rotatable turnover wheel adjacent one end of said chute, reciprocating feeding devices for successively engaging and projecting said articles from said yieldable devices in said chute and for moving them into said turnover wheel, actuating means for rotating said turnover wheel for inverting the articles carried therein, reciprocating transfer devices for conveying the inverted articles from said turnover wheel, and a table located adjacent said turnover wheel for receiving said inverted articles.

2. An apparatus for handling flanged can ends 60 and the like, comprising in combination, a chute for flanged can ends, yielding devices in said chute for holding said ends therein with one

face of their flanges turned up, a rotatable turnover wheel located below said chute and formed of cooperating grooved discs, a pair of grooves being adapted to be brought into register with the discharge end of said chute, feeding devices for first removing a said can end from said chute by withdrawing it from said holding devices and then moving it into said positioned disc grooves, and actuating means for rotating said discs to carry their grooves up and over and to turn over 10 said can end, therein so that its opposite flange face is turned up.

3. An apparatus for handling flanged can ends and the like, comprising in combination, a chute for flanged can ends, yielding devices in said chute for holding said ends therein with one face of their flanges turned up, a rotatable turnover wheel located below said chute and formed with 15 cooperating grooved discs, a pair of grooves being adapted to be brought into register with the discharge end of said chute, feeding devices for first removing a said can end from said chute by withdrawing it from said holding devices and then moving it into said positioned disc grooves, a table located adjacent said turnover means, 20 actuating means for rotating said discs to carry their grooves up and over and to bring them in registration with the top of said table and to turn over said can end therein so that its opposite flange face is turned up, and transfer 25 devices for conveying said turned over can end from said disc grooves on to said table.

4. An apparatus for handling flanged can ends and the like, comprising in combination, a chute for flanged can ends, yielding devices in said 30 chute for holding said ends therein with one face of their flanges turned up, a rotatable turnover wheel located below said chute and provided with a shaft and cooperating grooved discs mounted on said shaft, a pair of grooves being 35 adapted to be brought into register with the discharge end of said chute, a table located adjacent said turnover wheel, feeding devices for first removing said can end from said chute by withdrawing it from said holding devices and then moving it into said positioned disc grooves, actuating means for intermittently rotating said 40 turnover wheel shaft and discs to present a said pair of grooves first to said chute for receiving the can end from said feeding devices and thence into register with the top of said table during 45 which time the rotation of said turnover wheel turns over said can end therein and turns up its opposite flange face, and means for adjustably securing said grooved discs on said shaft to 50 permit their adjustment for different sizes of can ends.

5. An apparatus for handling articles such as can parts and the like, comprising in combination: a chute for said articles, spring controlled 55 yieldable devices in said chute for holding said articles therein, a rotatable turnover wheel adjacent one end of said chute, reciprocating feeding devices for successively engaging and projecting said articles from said yieldable devices in said chute and for moving them into said turnover wheel, actuating means for rotating said turnover wheel for inverting the articles carried therein, and reciprocating transfer devices for conveying the inverted articles from said turnover wheel.

WILLIAM F. BUTLER.
